DESIGN FOR A COMBINED ASHTRAY AND BRACKET SUPPORT THEREFOR

Thomas E. Platt, San Francisco, Calif.

Application April 29, 1938, Serial No. 76,850

Term of patent 3½ years

To all whom it may concern:

Be it known that I, Thomas E. Platt, a citizen of the United States, residing at San Francisco, in the county of San Francisco, State of California, have invented a new, original, and ornamental Design for a Combined Ashtray and Bracket Support Therefor, of which the following is a specification, reference being had to the accompanying drawing, forming part thereof:

I claim:

The ornamental design for a combined ashtray and bracket support therefor, substantially as shown.

THOMAS E. PLATT.
